UNITED STATES PATENT OFFICE.

WILLIAM F. TUBESING, OF MILWAUKEE, WISCONSIN.

TIME-RECORDING WATCH.

1,235,260.

Specification of Letters Patent.

Patented July 31, 1917.

Application filed July 5, 1912. Serial No. 707,700.

To all whom it may concern:

Be it known that I, WILLIAM F. TUBESING, a citizen of the United States, and resident of Milwaukee, in the county of Milwaukee, and State of Wisconsin, have invented new and useful Improvements in Time-Recording Watches, of which the following is a description, reference being had to the accompanying drawings, which are a part of this specification.

This invention relates to time recorders to be carried in the pocket as an ordinary watch and adapted to trace a record on a dial to indicate the time elapsing between the various adjustments thereof and thus form a permanent record of the duration of the succeeding events for which the adjustment is made.

The invention comprises a watch provided with a disk on its face which turns instead of having hands to turn over a dial in the usual manner and this disk may be graduated by radial lines indicating time as well as preferably having concentric circles for the various adjustments of a sliding indicator which is adapted to mark upon the disk as the disk turns therebeneath.

Another object of the invention is to provide a disk graduated as desired and provided with a coating of a wax-like material which will receive the impressions of the stylus of the sliding indicator and constitute a permanent record thereof if so desired, but which may be readily restored to its original condition free from any trace of preceding record by the application of heat.

With the above and other objects in view the invention consists in the recording watch as herein claimed and all equivalents.

Referring to the accompanying drawings in which like characters of reference indicate the same parts in the different views:

Figure 1 is a plan view of a time recording watch constructed in accordance with this invention;

Fig. 2 is a sectional view thereof;

Fig. 3 is a detail, perspective view of the record disk and its support.

In these drawings 10 indicates an ordinary watch mechanism without dial or hands but having a disk 11 mounted thereon in place of the hour hand so that it completes one rotation in twenty-four hours. The invention is not confined to any particular time for the rotation of the disk. The disk 11 is provided with a pair of lugs 12

standing out from its face and a record disk 13 is correspondingly provided with a pair of openings 14 to fit upon said lugs 12 so that the record disk is driven by the watch 60 works at the speed of disk 11. The record disk 13 constitutes a disk of paper or other material to receive an impression or to have a record line traced thereon by means of a stylus 15 carried by a slide 16 working in a 65 slotted guide 17 which is attached to the rim of the watch case and extends part way across the record disk. The slide 16 has a lug 18 projecting from it by means of which it may be adjusted so that the bearing of the 70 stylus 15 on the record disk 13 may be between any two of the concentric circles which are preferably marked on the face thereof. When permanent records are desired the record disk 13 may be of paper and the stylus 75 80 85 90 95 100 105 110

consist of a pencil point for tracing the record thereon, but if temporary records are desired, I prefer to make the disk 13 of sheet metal and coat the engraved or otherwise marked face thereof with paraffin or similar wax-like material which will take the impression of the stylus in its travel therebeneath, leaving a clearcut line to constitute the time record, but which by the gentle application of heat, as by holding a lighted match beneath the disk, will be restored to its original condition without trace of the former record and will then be adapted to have a new record engraved therein. The radial lines of the record disk are preferably provided with the numerals 1 to 12 representing the hours and on starting the watch it may be set to the correct time by turning the record disk in the usual manner for adjusting the hands of the watch until the proper time on the recording disk is in the radial line of adjustment of the travel of the stylus of the indicator. During such setting of the watch the stylus may be either moved to a position where it is beyond the edge of the recording disk or it may be sprung away from the disk, the connection for the guide 17 being of a spring nature which will permit of such movement. When the watch is set, the indicator slide 16 is moved to bring the stylus 15 between two of the concentric circles on the record disk. The watch is closed and is left in this condition until the occurrence of some event which is desired to be timed, when the indicator slide is merely moved to change the stylus from one position to another and thus

throughout the day the various changes in position of the stylus and the time at which such changes were made are indicated by the record cut by the stylus in the wax 5 coating of the record disk or otherwise marked upon the record disk. At the end of the day the record disk may be readily removed by slipping it off of the lugs 10 12, the indicator slide being sprung away from the disk 11 to permit thereof. The record disk may be replaced by another if it is to constitute a permanent record, or the record may be obliterated and the disk restored to its original condition by the application 15 of heat if the record is only temporary. The record disk is as readily replaced as removed and is immediately placed in condition to receive a new record.

In practice this time recorder is found of 20 great value to men who have to divide their time each day between different classes of work for which different charges are made or between different pieces of work charged to different parties. Thus, the space between 25 two of the circles may represent one class of work and the space between other circles represent other classes of work, so that the time given by the individual carrying the watch to the several classes of work in any 30 particular day will be indicated by the portion of the record line left by the stylus within the respective spaces. The operator does not have to charge his memory with the details 35 regarding the time of changes made during the day, nor does he have to keep a

memorandum book for the purpose, but it is only necessary for him to shift the stylus each time he changes the work and this may soon become a matter of habit. The invention may be made of the size of an ordinary 40 watch so as to be convenient for carrying.

What I claim as new and desire to secure by Letters Patent is:

1. A record for recording means having suitable guide lines thereon and provided 45 with a coating of wax capable of containing a record line having relation to the guide lines and capable of having such record line eradicated by the application of heat.

2. A record sheet for a time recording 50 watch, comprising a record disk having radial lines thereon representing units of time measurement and concentric circles thereon representing the different conditions under which the time may be spent, and adapted to 55 have a stylus engage it at any of the record areas between the concentric circles, and a transparent wax coating on the record disk permitting the lines of the disk to show therethrough and adapted to have the path 60 of travel of the stylus traced thereon and capable of having such record eradicated therefrom by the application of heat.

In testimony whereof, I affix my signature, in presence of two witnesses.

WILLIAM F. TUBESING.
